UNITED STATES PATENT OFFICE.

JOHN H. ZOERMAN, OF CHICAGO, ILLINOIS.

THREAD-CUTTING TOOL.

1,426,441.

Specification of Letters Patent. Patented Aug. 22, 1922.

Application filed June 14, 1920. Serial No. 388,725.

To all whom it may concern:

Be it known that I, JOHN H. ZOERMAN, a citizen of the United States of America, residing at Chicago, in the county of Cook 5 and State of Illinois, have invented certain new and useful Improvements in Thread-Cutting Tools; and I do hereby declare the following to be a full, clear, and exact description of the invention, such as will enable others skilled in the art to which it appertains to make and use the same.

This invention relates to thread cutting tools and is primarily concerned with various useful and novel improvements in the 15 construction of the tool shown in U. S. Patent No. 1,005,604, issued October 10, 1911, having reference chiefly to a novel way of attaching the operating handles thereto so that the same may be extended for use when 20 the tool is to be operated, or folded on to the body of the tool to compact the same for shipment, and to a further sectional construction of the thread cutting dies whereby if any die section becomes broken or otherwise 25 useless, it may be readily removed and replaced by another without the necessity of throwing away remaining good portions of the die as is necessary when the dies are made in one piece. Further objects and purposes of the invention, together with novel 30 constructions and arrangements of parts for attaining the same will appear fully and in detail as understanding of the invention is had from the following description, taken 35 in connection with the accompanying drawings, in which,

Fig. 1 is an elevation of the thread cutting tool.

Fig. 2 is a plan of the construction shown 40 in Fig. 1.

Fig. 3 is a view similar to Fig. 1, but with the handles in folded position and with the inner end of one handle shown in section to disclose its method of attachment to the 45 tool.

Fig. 4 is a fragmentary longitudinal section through the inner end of one handle and the adjacent parts of the tool.

Fig. 5 is a fragmentary enlarged partial 50 sectional and elevational view showing the manner in which the sectional dies are secured detachably in place on the tool.

Fig. 6 is a perspective view of one of the sectional dies, and

Fig. 7 is a fragmentary transverse section

through one of the sectional dies and the adjacent bar on which it is mounted.

Like reference characters refer to like parts in the different views of the drawings.

In the construction of the tool, two bars 60 1 and 1^a are used, each being widened at its ends as indicated at 2, 2^a there being a relatively long recess at each side of the bar between the ends 2, 2^a in which the dies, hereafter described, are located. At one end 65 the ends of the bars are divided to make spaced apart ears 3, while a lug 4 projects outwardly from the opposite end of each bar.

Spaced apart ears 5 are formed integral 70 with the bars 1 and 1^a at opposite ends thereof, projecting from the widened portions thereof, and between said ears members 6 are pivotally mounted, each having a threaded shank 7 on which a hollow handle 75 8 is secured. Each of said handles is made from tubing closed at its outer end and interiorly threaded at its inner end. When in the position shown in Fig. 1, the handles may be turned to engage against one side of 80 the ears 5 and will be locked in such position against movement. When the tool is not in use, the handles may be turned to loosen their engagement with the ears, after which the handles with the connected members 6 85 may be turned to the position shown in Fig. 3 and then turned against the opposite sides of the ears, again locking the handles against movement.

A link 9 lies at its ends between the ears 90 3 at the ends of bars 1 and 1^a and is pivotally connected to said ears. An arm 10 is pivotally connected to one of the lugs 4 at the opposite end of the bar 1 and passes over and detachably engages the similar lug 95 on bar 1^a, a set screw 11 threading through the end of the arm against said lug to secure it detachably in place. It is evident that on loosening the set screw 11, the bars 1 and 1^a may be turned one around the other 100 so as to bring the dies carried on opposite sides thereof into operative relation to each other. The notched disk 12 at the point of pivotal connection of one end of the link 9 to the bar 1 is similar to a like notched adjusting disk in the patent above mentioned and is for the same purpose, to adjust the difference between the dies on the bars. As it forms no novel portion of the present invention it is not further described.

In the elongated recesses on each side of the bars 1 and 1^a, a plurality of sections of dies are located. On the adjacent sides of the bars, as shown in Figs. 1 and 3, three 5 of these sections are shown, a middle section 13 and two end sections 14. Each is grooved longitudinally in its under side as indicated at 15 so as to fit over a corresponding rib 16. The middle section is formed 10 at its base and at each end with an extension 17 and the adjacent portions of the end sections 14 are cut away and notched so that said extensions 17 may pass therein as shown. Removable securing screws 18 of the 15 form shown in Fig. 5 are threaded into the enlarged ends 2 of the bars, the same engaging with the end sections 14, forcing them to place and holding them securely against movement. The middle section is held by 20 the end sections 14 together with the engagement with rib 16 which prevents any possible movement which would bring the extensions 17 out from under the overhanging parts of the end sections 14.

If more than three sectional dies on a side are used, a slight difference in construction is used. I have shown five sections to the dies on the outer sides of bars 1 and 1^a in Fig. 1, the middle section 13^a and the end 25 sections 14^a 14^b being the same as sections 13 and 14 heretofore described so far as the under side construction is concerned while the additional sections 19 are provided with extensions 17^a at one end to go in the recesses 30 in the end sections 14^a and recesses at the other end to receive the extensions on the middle section 13^a, as shown. The sections 35 are held in place by screws 18 the same as heretofore described with reference to the 40 three section construction.

Each of the sections is made as one half of a thread cutting die and cooperates with the similar section on the opposite bar to make a complete cutting die. If any section becomes broken or otherwise useless, 45 it is easy to replace it with a new section without throwing away the other good sections. This is an important feature of my invention, the value of which is evident. The invention is defined in the appended 50 claims and I consider myself entitled to all constructions which come within the scope of such claims.

I claim:

1. A device of the character described 55 comprising a pair of members adapted to lie substantially parallel to each other and having coacting die faces on adjacent sides, a handle pivotally connected at an end of each member, said members having the handles attached thereto at opposite ends, and said handles being movable from folded position against said members to operative position extending from said members, and means for locking the handles against movement in either position.

2. A device of the character described comprising a pair of members adapted to lie substantially parallel to each other and having coacting die faces on adjacent sides, 60 a pair of ears projecting laterally from each member adjacent an end thereof, said ears projecting from opposite ends of the members, a member having a threaded shank pivotally mounted between the ears of each pair of ears, and a handle threaded on to each of said shanks, substantially as and for the 65 purposes described.

In testimony whereof I affix my signature.
JOHN H. ZOERMAN,
